UNITED STATES PATENT OFFICE.

JOHN W. COAST, JR., OF TULSA, OKLAHOMA, ASSIGNOR, BY MESNE ASSIGNMENTS, TO THE PROCESS COMPANY, A CORPORATION OF MARYLAND.

ART OF DISTILLING HYDROCARBONS.

1,250,798.

Specification of Letters Patent. Patented Dec. 18, 1917.

Application filed October 23, 1916. Serial No. 127,128.

To all whom it may concern:

Be it known that I, JOHN W. COAST, Jr., a citizen of the United States, residing at Tulsa, in the county of Tulsa and State of Oklahoma, have invented a new and useful Improvement in the Art of Distilling Hydrocarbons, of which the following is a specification.

My invention relates to the treatment of hydrocarbons, such for example as the distillates of crude petroleum, the object being to reduce the specific gravity of such hydrocarbons, and to otherwise beneficially alter their properties. More specifically stated, one of the objects of the invention is to improve the known methods of obtaining gasolene from the products which result from the ordinary distillation of crude petroleum, and with this object in view, the new method includes certain combinations of steps whereby the objectionable odor and color is almost entirely eliminated through my distillation process, thus economizing in the use of the acid ordinarily used in treating cracked products, at the same time materially reducing the percentage of unsaturated hydrocarbons. Another object is to predetermine the specific gravity of the product in such a manner that a substantially uniform product of relatively low boiling point may be obtained by a rapid cracking operation, thereby increasing the capacity of the distilling apparatus without reducing the value of the resultant product. A further object is to accomplish all of the foregoing results and at the same time obtain a very high percentage of the desirable product from the comparatively heavy and less valuable hydrocarbons.

Figure I is a diagrammatical view of an apparatus adapted for use in carrying out the new method.

Fig. II is a section on line II-II, Fig. I. 1 designates a retort or still provided with a pressure chamber 2 and a vapor pipe 3 leading from said pressure chamber to the condenser 4. A pressure regulating valve 5 is located in the vapor pipe at a point between the retort and condenser. A steam pipe 6 leading into the pressure chamber 2 communicates with a discharge member 7 arranged within said pressure chamber. The bottom face of this discharge member is provided with a multitude of small discharge ports for the discharge of a multitude of

fine streams of steam into the pressure chamber 2.

Although I have shown and described a specific structure adapted for use in following my method, it is to be understood that the illustration is merely diagrammatical and that any suitable apparatus may be used in connection with the method herein claimed.

The new method may be used in distilling various heavy hydrocarbon products resulting from the treatment of crude petroleum, but is more particularly adapted for use in distilling such inexpensive heavy hydrocarbons having a boiling point of about 350 degrees F. to 800 degrees F., the most beneficial results being obtained from hydrocarbons having a boiling point ranging from 450 degrees F. to 700 degrees F. The substances to be treated are introduced into the retort in any suitable manner, and the valve 5 is adjusted to insure a desired predetermined pressure in the retort and the pressure chamber 2. The retort is heated to subject its contents to a temperature ranging from about 600 degrees F. to 800 degrees F., the valve 5 being regulated to obtain a pressure preferably between 50 and 150 pounds per square inch in the retort 1, pressure chamber 2, and in that portion of the vapor pipe 3, which lies between the valve and pressure chamber.

The vapors rise from the contents of the retort and are conducted into the pressure chamber 2, and at this point the temperature of said vapors is reduced to an approximately predetermined degree, as will be hereinafter described, for the purpose of predetermining the specific gravity of the product. The vapors of relatively high boiling point liquefy and return from the pressure chamber to the retort, and the remaining vapors are conducted through the pressure regulating valve 5 to the condenser 4 where they are condensed under approximately atmospheric pressure.

The temperature of the steam flowing through the pipe 6 may vary from about 250 degrees F. to 500 degrees F., and the admission of steam to the pressure chamber 105 may be regulated by adjusting the valve 8.

When the distilling apparatus is in operation, the valve 5 is regulated and the temperature of the retort is regulated to maintain a substantially constant pressure and 110

temperature in the retort. The temperature is usually greater than 600 degrees F. and as a consequence some of the heavier hydrocarbons vaporize and tend to flow toward 5 the condenser with the more volatile hydrocarbons. Since one of the objects is to obtain a product of a predetermined specific gravity, it would obviously be a disadvantage to permit the relatively heavy hydrocarbons to reach the condenser. I, therefore, regulate the valve 8 to control the flow of steam into the pressure chamber 2, thus reducing the temperature of the vapors to such an extent that the hydrocarbons 10 having the relatively high boiling point will liquefy and return to the retort, allowing the hydrocarbons of a predetermined and relatively low boiling point to pass from the pressure chamber to the condenser. 15 The liquid passing from the condenser may be readily tested to determine its specific gravity and if the desired product is not obtained, the steam controlling valve 8, may be adjusted with the result of varying the 20 specific gravity of the product, thereby enabling the operator to predetermine the approximate boiling point and specific gravity of the product without varying the substantially constant pressure and temperature 25 in the retort. It will of course be desirable to regulate the temperature and pressure to obtain the most satisfactory results. When the steam is properly regulated, the product may be recognized by its 30 specific gravity; its range of boiling points; its distinctive color and odor; and a relatively small volume of fixed gas will flow from the receiving tank. Any one of the characteristics of the product may be readily 35 observed by the operator to guide him in the regulation of the steam, and to be absolutely certain that the test or observation is correct, it may be corroborated by noting one of the other distinctive qualities of the 40 product, or by the rate of flow of the fixed gas. Manifestly, a substantially uniform product may be easily obtained by following this method.

To insure the most efficient results, the 45 vapors under pressure are preferably circulated from the retort in the form of a stream and while confined in a restricted space by the pressure chamber 2, this stream of hot vapors is acted upon by a multitude 50 of streams of comparatively cool steam, passing from the discharge member 7. The steam is thus thoroughly mingled with the hot vapors so as to reduce their temperature to such a degree (for example 400 degrees 55 F.) that all of the hydrocarbons having

a boiling point above a predetermined degree will return to the retort, while the hydrocarbons having a boiling point below said predetermined degree will pass to the condenser as previously pointed out.

Since the specific gravity of the product may be positively controlled, the temperature and pressure may be regulated to obtain a very rapid distilling operation thus increasing the capacity of the apparatus 70 without injuriously affecting the properties of the product.

In actual practice, I have found that all of the foregoing desirable results are obtained by my method, and furthermore, the 75 objectionable odor and color are almost entirely eliminated from the product.

I claim:

1. In the art of treating high boiling petroleum hydrocarbons, the method which comprises heating, vaporizing and cracking such hydrocarbons under a pressure greater than fifty pounds, to obtain a product of lower boiling point, introducing an aqueous fluid into the vapor at a point above the liquid 80 level in the retort, said aqueous fluid being cooler than said vapor, thereby causing the hydrocarbons of relatively high boiling point to condense and return for further cracking treatment, and conducting the remaining vapor to a condenser.

2. In the art of treating high boiling petroleum hydrocarbons, the method which comprises heating, vaporizing and cracking such hydrocarbons under a pressure greater than fifty pounds, to obtain a product of lower boiling point, conducting the vapor to a plane higher than the retort, introducing an aqueous fluid into the vapor at the last mentioned point, said aqueous fluid 85 being cooler than said vapor, thereby causing the hydrocarbons of relatively high boiling point to return to the retort, and conducting the remaining vapor to a condenser.

3. In the art of treating high boiling petroleum hydrocarbons, the method which comprises heating, vaporizing and cracking such hydrocarbons under a pressure greater than fifty pounds, to obtain a product of lower boiling point, introducing steam, of a temperature lower than the vapor of said hydrocarbons, into said vapor at a point above the liquid level in the retort, thereby causing the hydrocarbons of relatively high 110 boiling point to condense and return for further cracking treatment, and conducting the remaining vapor to a condenser.

JOHN W. COAST, JR.
